UNITED STATES PATENT OFFICE.

CHARLES E. THOMPSON, OF NEW HAVEN, CONNECTICUT.

DESIGN FOR A COACH-LAMP.

SPECIFICATION forming part of Design No. 12,947, dated May 23, 1882.

Application filed April 8, 1882. Term of patent 3½ years.

To all whom it may concern:

Be it known that I, CHARLES E. THOMPSON, of New Haven, in the county of New Haven and State of Connecticut, have invented a new 5 Design for Coach-Lamps; and I do hereby declare the following, when taken in connection with accompanying drawing and the letters of reference marked thereon, to be a full, clear, and exact description of the same, and which 10 said drawing constitutes part of this specification, and represents a side view.

This invention relates to a design for carriage or coach lamps, and particularly to that 15 part of the lamp called the "body," or the portion into the sides of which the glass is introduced; and it consists in the peculiar configuration of the side panels, as shown in the accompanying illustration and hereinafter described.

20 The general outline of the lamp above and below the body may be of any known or de-

sirable shape, that constituting no part of this design, except that a base and tip of some character are necessary to the lamp.

The side of the lamp represents a quadrant 25 in shape, the bottom line being horizontal, the side vertical, and the curve running from the top of the side down to meet the bottom.

I prefer to make the vertical side of this lamp to the front; but it may be to the rear 30 without materially changing the effect of the design, the essential feature of the design being the quadrant-shaped side, as shown in the accompanying illustration.

I claim—

35 The design for carriage-lamps, consisting of the quadrant-shaped side, as described, and shown in the accompanying illustration.

CHARLES E. THOMPSON.
